UNITED STATES PATENT OFFICE

2,356,947

PACKER FOR PRESSURE DRILLING HEAD

Albert Pranger and Samuel Allen Guiberson, III,
Dallas, Tex., assignors to The Guiberson Corporation, Dallas, Tex., a corporation of Delaware

Application April 11, 1941, Serial No. 388,030

5 Claims.

(Cl. 286—16)

This application is a continuation in part of our application on Pressure drilling head, Serial No. 239,458, filed November 8, 1938, now Patent No. 2,303,090, issued November 24, 1942. The present application relates to the particular form of packer shown in said application 239,458 and in particular relates to the reinforcing means for the packer.

The invention may be better understood by referring to the attached drawing in which,

Fig. 1 is a vertical view principally in cross-section,

Fig. 2 is a cross-sectional view of the packer, and

Fig. 3 is a cross-sectional view on the line 3—3 of Fig. 2.

A head 1 is secured to a casing 2 by a coupling 3. The head 1 is provided with a shoulder 4 on which is seated the lower end of a corrugated packer 5. A gland 6 telescopes within the upper end of the head 1 and the lower end of the gland serves as a means to compress or push downwardly the upper end of the packer. Bolts 7 are secured in wells 8 at the upper end of the head 1 and nuts 9 may be screwed downwardly to force the gland downwardly to cause the packer to pack off between the head 1 and the pipe 10 passing through the packer. As fully described in said application 239,458, the packer is sufficiently resilient to permit the passage therethrough of collars and round or square kellys. In other words, it is sufficiently flexible to receive any kind of a kelly or pipe within certain limits.

This packing is frequently subjected to heavy pressures. It is apparent that the lower end of the packer would be subjected to these pressures and there would be a tendency to move the lower end of the packer upwardly so that the greater the pressure encountered, the tighter the packer would engage the head 1 and the pipe extending through the packer. It is to be noted that there would be a tendency for the upper end of the packer, when the packer was subjected to great pressure, to flow upwardly between the gland 6 and the pipe 10. We have, therefore, provided a metallic ring 11 provided with holes 12 near the upper end of the packer. We have also provided a similar ring near the lower end thereof so as to counteract any tendency of the packer to flow downwardly between the lower end of the head and the pipe in case the gland exerted great pressure on the pipe. The function of these rings 11 is, therefore, to hold the upper and lower ends of the packer against any tendency to flow, that is, the upper and lower ends are reinforced. The composition of the resilient packer extends through the holes 12 and the packer is bonded to the upper and lower sides and the outer and inner surfaces of the rings as well as to the walls of the holes. The rings are preferably made of metal

forming a continuous non-expansible ring. We prefer not to place these reinforcing rings at the extreme ends of the packer for the reason that if they were there placed the packer might tear away from the rings. We, therefore, place the rings near the ends but securely embedded therein so that the packer will not tear away from the rings.

We realize that many changes may be made in the specific form of the invention shown by way of illustration herein. We, therefore, desire to claim the same broadly except as we may limit ourselves in the appended claims.

Having now described our invention, we claim:

1. A corrugated packer having outwardly flaring upper and lower ends and rigid reinforcing rings embedded in the packer in the outwardly flaring upper and lower ends, each of said rings being provided with a plurality of holes through which the packer protrudes.

2. A corrugated packer having outwardly flaring upper and lower ends and rigid reinforcing rings embedded in the packer in the outwardly flaring upper and lower ends, each of said rings being provided with a plurality of holes through which the packer protrudes, the packer being bonded to the sides and edges of the ring and to the side walls of the holes.

3. A packer having outwardly extending upper and lower ends and having a longitudinally extending bore and rigid reinforcing rings in the said outwardly extending upper and lower ends to prevent the said ends moving radially inwardly.

4. In combination with a hollow head having a seat and a hollow gland having a seat spaced from the seat of the head and a pipe or kelly passing through said head and gland, a packer to pack off the space between said head and pipe or kelly,

40 said packer having outwardly extending upper and lower ends adapted to seat on the seats of said gland and head respectively, and rigid rings embedded in said outwardly extending upper and lower ends to prevent said ends from moving radially inwardly off of said seats.

5. In combination with a hollow head having a seat and a hollow gland having a seat spaced from the seat of the head and a well instrument passing through said head and gland, a corrugated packer to pack off the space between said head and well instrument, said packer having outwardly extending upper and lower ends adapted to seat on the seats of said gland and head respectively, and rigid rings embedded in said outwardly extending upper and lower ends to prevent said ends from moving radially inwardly off of said seats.

ALBERT PRANGER.
SAMUEL ALLEN GUIBERSON, III.
